CLAIM

The ornamental design for a vehicle taillight as shown and described.

DESCRIPTION

FIG. 1 is a front view of a first embodiment a vehicle taillight showing the present design;
FIG. 2 is a left side view thereof;
FIG. 3 is a front and left side perspective view thereof;
FIG. 4 is a front, top and left side perspective view thereof;
FIG. 5 is a front view of a second embodiment of a vehicle taillight showing the present design, the second embodiment being a mirror image of the first embodiment;
FIG. 6 is a right side view thereof, being a mirror image of FIG. 2;
FIG. 7 is a front and right side perspective view thereof, being a mirror image of FIG. 3; and,
FIG. 8 is a front, top and right side perspective view thereof, being a mirror image of FIG. 4.
The features shown in half-tone and bordered by broken lines form no part of the claimed design.
The "IQ LIGHT" lettering forming part of the claimed design is a registered trademark of Volkswagen Aktiengesellschaft.

1 Claim, 8 Drawing Sheets
